E. D. Harris, Jr., INVENTOR.

ATTORNEYS

UNITED STATES PATENT OFFICE.

EBENEZER D. HARRIS, JR., OF DENVER, COLORADO.

ROTARY SCRAPER.

Application filed December 13, 1919. Serial No. 344,509.

To all whom it may concern:

Be it known that I, EBENEZER D. HARRIS, Jr., a citizen of the United States, residing at the city and county of Denver and State 5 of Colorado, have invented certain new and useful Improvements in Rotary Scrapers; and I do declare the following to be a full, clear, and exact description of the invention, such as will enable others skilled in the 10 art to which it appertains to make and use the same, reference being had to the accompanying drawings, and to the characters of reference marked thereon, which form a part of this specification.

15 My invention relates to improvements in scrapers of the class used in connection with road work and excavation, and of the class which are drawn by horses or traction, which are hitched or connected to drawbars 20 with which the scoop is provided, handles extending rearwardly for use by the operator or man in charge.

My object is to provide a construction of this class in which the scoop or body 25 member is pivotally connected, both with the drawbars and the handles in the rear, the drawbars and handles being so connected with the scoop or body that normally there is a tendency for the scraper when 30 loading to tip forward by reason of the engagement of the front edge of the scoop with the ground. In order to overcome this normal tendency, a latch construction operable from the handles or from a single bar 35 extending rearwardly, and carrying means for releasing spring-actuated latches, which normally lock the shovel or body member against rotary movement, is provided. In this event, it is only necessary to release the 40 latches which maintain the scoop in the loading position, in order to allow the latter to dump, which will be automatically accomplished. If it should be desired, the operator may lift slightly upon the handles 45 or handle before releasing the latches, but it is the intention to have the dumping absolutely automatic when the latches are released.

Again, these same latches engage notches 50 or recesses in parts stationary with the scoop when the latter is in the dumped position, but as the heavier part of the scoop is then forward, the latter will move into the loading position as soon as the latches are released for the purpose. In this way it is necessary only for the operator to attend

to the releasing of the latches, since these latches are spring-actuated and automatically return to the latched position as soon as the scoop is properly arranged or positioned.

Having briefly outlined my improvement, I will proceed to describe the same in detail, reference being made to the accompanying drawing, in which is illustrated an embodiment thereof. In this drawing:

Fig. 1 is a perspective view of a scraper equipped with my improvement, showing the same in the loading position.

Fig. 2 is a similar view, showing the 70 same in the dumped position.

Fig. 3 is a perspective view, illustrating a modified form of construction.

Fig. 4 is a side elevation on a larger scale than Figs. 1 and 2, looking at one side 75 of the scraper, which is largely broken away.

Fig. 5 is a section taken on the line 5—5 Fig. 4, viewed in the direction of the arrows.

Fig. 6 is a section taken on the line 6—6, Fig. 5, looking toward the right.

Referring first to the form of construction shown in Figs. 1, 2, and 4 to 6, inclusive, let the numeral 5 designate the scoop or body 85 of the scraper, each side 6 of which is provided with a sort of hub 7, having parts 8 and 9 on opposite sides which are provided with notches 10, adapted to receive latches 12, with which rods 13 are provided, these 90 rods being spring-actuated to normally maintain the latches in engagement with the notches in the parts 8 or 9, as the case may be. As shown in the drawing, the rods 13 are mounted on handles 14, each rod being connected with a handpiece 15, pivotally connected as shown at 16 with the adjacent handle bar 14. Each rod 13 passes through a perforated guide 17, fast on the handle bar, and is provided with a stop 18, 100 which is also perforated to allow the rod to pass through the stop as well as the guide 17 on the handle bar. A spiral spring 19 is located between the stop and the guide, whereby the rod is spring-actuated, to hold 105 the latch 12 in position to engage the recess 10 of the part 8 or 9, according to the position of the scoop, as heretofore explained. The forward extremities of the handle bars 14, as well as the rear extremities of the 110 drawbars 20, are pivotally connected with journals 21, with which the discs 7 are pro-

vided. As shown in the drawing, the rear extremities of the drawbars are provided with housings 23, which have inwardly projecting parts 24 and 25, between which the forward extremities 26 of the hand-bars are located, thus limiting the movement of the hand-bars with reference to the drawbars. It should be understood, however, that the parts 24 and 25 do not extend into the path of the parts 8 and 9 or the discs 7, since the parts 7, 8 and 9 rotate with the scoop. As shown in the drawing, the parts 8 and 9 are cast integral with the discs 7, but extend laterally slightly beyond the disc, as best illustrated in Fig. 5. This is for the purpose of allowing ample room for the latch rods 13, the inner portions of the handle bars being bent outwardly, as shown at 27, the bent parts being perforated to receive the latch rods, the bent parts 27 being in alignment with the members 8 and 9, containing the notches 10. In this form of construction the scoop will maintain the position illustrated in Fig. 1 until it is loaded, and as soon as this occurs the operator will press the handpieces 15, carried by the handle bars, sufficiently to release the latches 12 when the scoop will move to the dumped or unloaded position (see Fig. 2). As soon as this occurs the latches 12 will engage the notches or recesses 10 of the parts 9, when the scoop will be locked in the dumped position, and may be moved along in this position until it is desired that it should assume the loading position, when the operator will again press the handpieces 15 toward the handle bars, which will release the latches and the scoop will return automatically to the loading position by virtue of the fact that the scoop portion forward of the journals when in the dumping position is heavier than that in the rear. However, if it should be necessary at any time, either when the scoop is in the loading or dumped position, the movement of the scoop may be facilitated or helped by lifting slightly upon the hand-bars before releasing the latches.

In the form of construction shown in Fig. 3, a single hand-bar 28 only is employed. The scoop 29, however, is provided with a U-shaped frame 30, consisting of a top-bar 31, and two downwardly extending or vertically disposed parts 32, having offsets 33 perforated to receive rods 34, which carry latches which engage either of two notches 35, formed in discs or reinforced parts 36, with which the opposite sides of the scoop are provided. The lower portions 37 of the parts 32 are pivotally connected with journals 38, formed on the notched members 36. The draw-bars 39 are also pivotally connected with the said journals. The rear ends of the draw-bars 39 have a housing 40, equipped with projections 41 and 42, between which the parts 37 extend,

allowing a limited play for the said parts between the said projections. The upper extremities of the latch rods 34 are pivotally connected with arms 43 of bell crank levers, which are fulcrumed as shown at 44, 70 their opposite arms 45 being respectively connected with rods 46, whose inner extremities respectively pivotally engage arms 47 and 48 of a lever 49, pivotally connected with the top part 31 of the frame 30. A 75 rod 50 is pivotally connected with a third arm 51 of the lever 49, the outer extremity of the rod 50 being pivotally connected as shown at 52, with a handpiece 57, the latter being pivotally connected with the hand-bar 28, as shown at 58. This rod passes through a guide lug 54, fast on the bar 28, the rod being provided with a stop 55 between which and the guide a spiral spring 56 is located. This spring serves to maintain the lever 49 and the levers 44 in such position as to maintain the latches in engagement with either set of notches 35 of the parts 36.

Assuming that the scoop is in the loaded 90 position (see Fig. 3) when it is desired to dump it, the handpiece 57 is pressed toward the hand-bar, which movement actuates the rod 50 to release the latches through the medium of the mechanism heretofore described. 95 The scoop will then assume the dumped position, when the latches will re-engage another set of recesses 35. Then, when it is desired that the scoop should assume the loading position, the handpiece 57 is again 100 actuated when the scoop will automatically assume the proper position.

It may be assumed that the latches of the construction shown in Fig. 3 are substantially the same as in the other form of construction, reference being made particularly to Fig. 6 where the lower extremities of the latch rods are provided with latches 12. The two sets of recesses 35 will be required in the form of construction shown in Fig. 110 3, the same as in the other forms of construction.

I claim:

1. A scraper having a scoop whose opposite sides are provided with parts having 115 journals, pull-bars pivotally connected with said journals, hand bars also pivotally connected with the journals, the rear extremities of the pull-bars having housings provided with parts extending laterally therefrom on opposite sides of the handbars to limit the independent movement of the latter in both directions.

2. A scraper having a scoop whose opposite parts are provided with parts having 125 journals, pull bars pivotally connected with said journals, a U-shaped bar pivotally connected with the journals, a lost motion connection between the ends of the pull bar and the ends of the U-shaped bar, members se- 130

cured to the opposite sides of the scoop and provided with oppositely disposed notches, spring actuated latches normally engaging said notches, and rods carried by the said U-shaped bar and connected in operative relation with the latches for releasing purposes.

3. A scraper having a scoop whose opposite parts are provided with parts having journals, pull bars pivotally connected with 10 said journals, a U-shaped bar pivotally connected with the journals, a lost motion connection between the ends of the pull bar and the ends of the U-shaped bar, members se-

cured to the opposite sides of the scoop and provided with oppositely disposed notches, 15 spring actuated latches normally engaging said notches, rods carried by the said U-shaped bar and connected in operative relation with the latches for releasing purposes, and a lever secured to said U-shaped bar and 20 extending rearwardly of the scraper, said lever being provided with means for operating said latches.

In testimony whereof I affix my signature.

EBENEZER D. HARRIS, JR.
